UNITED STATES PATENT OFFICE.

EUGENE L. McGARY, OF CHICAGO, ILLINOIS.

PRESS.

1,301,954.

Specification of Letters Patent. Patented Apr. 29, 1919.

Application filed November 8, 1916. Serial No. 130,117.

To all whom it may concern:

Be it known that I, EUGENE L. McGARY, a citizen of the United States, and a resident of Chicago, in the county of Cook and State of Illinois, have invented certain new and useful Improvements in Presses, of which the following is a full, clear, and exact description.

The invention relates to presses operated by fluid pressure and more particularly to the type which is adapted to form a product between coacting male and female dies and in which a charge of material, such as bakelite, is placed into the female die by the operator.

In the operation of presses of this type, it has been found necessary to provide an ejector to move the product out of the female dies so that it can be removed from between the dies by the operator and these ejectors are usually operated by the fluid pressure mechanism which operates the movable die through a lost motion connection which causes the ejector to discharge the product at the end of the separating stroke and to be shifted into inoperative position during the initial operation of the operating or working stroke. This operation has been found to be dangerous if the operator placed the charge of material in the female die during the working stroke and after the ejector has been restored to its normal position or in the female die.

The primary object of the invention is to provide an improved press in which the ejector is operated by the fluid pressure mechanism at the end of the die-separating stroke with means for independently or manually restoring the ejector into the female die before the working stroke of the dies is commenced and thus afford opportunity for the operator to place the charge of material in the female die while the fluid pressure mechanism is at rest.

Other objects of the invention will appear from the following description.

The invention consists in the several novel features hereinafter set forth and more particularly defined by claims at the conclusion hereof.

In the drawings: Figure 1 is a side elevation of a press embodying the invention. Fig. 2 is a front elevation. Fig. 3 is a vertical transverse section, showing the parts in position assumed at the end of a separating or idle stroke, the ejector-mechanism

having been operated to move the product or molded articles out of the female dies. Fig. 4 is a vertical section taken on line 4—4 of Fig. 2, the parts being shown in position assumed at the end of a working stroke and when the articles have been formed by the dies. Fig. 5 is a similar view showing the parts in position assumed at the end of a separating stroke, the movable die-carrying member being at rest and the ejectors in position to permit the female dies to be charged with material. Fig. 6 is a similar view showing the parts in position assumed at the end of a separating stroke. Fig. 7 is a section taken on line 7—7 of Fig. 3. Fig. 8 is a horizontal section taken on line 8—8 of Fig. 3.

The press comprises standards 10 to which are rigidly secured by bolts 10' a bed 11. A die block 12 having female dies 14 therein is rigidly supported above the bed 11 by brackets 15 which are adjustably secured to the bed by bolts 16. Vertical supporting and guide rods 17 are rigidly secured in the bed 11. A cross-head 18 is vertically slidable on said rods and a die block 19 carrying male dies 20 is suitably secured between the rods 17 to the underside of the cross head. Fluid pressure mechanism for operating the cross head and male dies comprises a cylinder 21 which has a head 21' fixedly secured on the upper ends of the rods 17 by nuts 17', and a piston 22 to which the cross head 18 is secured and which is adapted to be operated for a working stroke to bring the dies together or by fluid pressure in the cylinder 21. It will be understood that suitable fluid pressure supply and controlling means (not shown) will be provided for the cylinder 21. The cylinder 21 and piston 22 constitute the fluid pressure mechanism for imparting the operative stroke to the movable die carrying member 18.

The mechanism for retracting the movable die carrying member and the piston 22 comprises a pair of quick-return cylinders 23 which are fixedly secured on head 21' at the sides of the cylinder 21 and are adapted to receive fluid under pressure to operate pistons 24. Each piston 24 has connected to its upper end a cross head 25 and a pair of vertical rods 26 connect each cross-head 25 and the movable die carrying member 18, the rods 26 being slidable through head 21' on the lower end of the cylinder 21.

Each female die is provided with an ejec-

tor-head 28 normally disposed in a recess 29 beneath said die and secured on the upper end of a stem 30 which is vertically slideable in and is extended through and below said 5 die block. The lower ends of the stems 30 are secured as by screw-threads 31 to cross bars 32 which are disposed in the space between the die-block supporting brackets 15 and are secured at their ends to end bars 34 10 by screws 33. Each of these end bars is secured, as by screw-threads 35, to the upper end of a pair of rods 36 which extend through and slide vertically in the bed 11. All of these rods 36 have their lower ends 15 secured by nuts 37 to a cross-head 38. A coil spring 39 is provided around each rod 36 and interposed between said cross-head and the bed 11 to normally and yieldingly hold the cross head 38 and the ejector sup- 20 porting and operating structure normally lowered so that the ejector heads 28 will lie within the recess 29. The mechanism for operating the ejector structure against the force of springs 39 comprises a trip lever 40 25 which is pivoted on a fulcrum pin 41 held in lugs 42 on the top of a cross-bar 43 which has its ends rigidly secured to rods 44 which extend through the bed 11 and have their upper ends secured to the head 18 which is 30 operated by the fluid pressure mechanism. Lever 40 comprises a pair of lugs or arms 47 which are adapted to act as abutments to engage and lift the cross-head 38 and the ejector operating structure, and an arm 48 35 extended around the rear of the cross-bar 43 and rearwardly offset with respect to the fulcrum pin so that it will, by gravity, operate to hold the arms 47 in position to operate the cross-head 38. A stop 43' limits 40 the movement of the lever in one direction. A treadle stirrup 49 is secured to and extends forwardly from arm 47 so that the operator, by depressing the front end of the stirrup with his foot, can operate the lever 45 to swing the arms 47 forwardly to release or trip the cross head 38. Upon such release, springs 39 will lower the cross head 38, rods 39, side bars 34, cross-bars 32 and the ejector stems 30 and heads 28. A stud 50 is secured in the cross head 38 and is slid- 50 ably mounted in bed 11 to coöperate with the rods 36 in vertically guiding the ejector mechanism.

In practice, it is desirable to adapt the 55 ejector mechanism for operation in connection with different die-blocks or die-blocks having different numbers or shapes of female dies therein. For this purpose, the transverse bars 32 are removably connected 60 by the screws 33 to the side bars 34. To adapt the ejector mechanism for different die-blocks or dies, it is only necessary to substitute transverse bars 32 with ejectors thereon arranged for a given die-block.

65 The operation of the invention will be as

follows: assuming the parts to be in position shown in Figs. 1, 2, 3 and 6, and assumed after a complete operation or at the end of a separating stroke of the press, the operator will first depress the treadle 49 to 70 shift the trip-lever 40 and release the cross-head 38 of the ejector mechanism, whereupon the springs 39 will operate the ejector mechanism downwardly so that the heads 28 will be disposed in recess 29. This operation 75 will be effected while the movable die-operating member 18 is at rest. Charges of material will then be placed in the female dies 14 in the die block 12. When the dies 14 have been thus charged, fluid under pres- 80 sure will be admitted to cylinder 21 to lower the die-carrying member 18 and force the dies 20 into the dies 14 to form the product or articles which, in the construction shown 85 consists of cup-shaped or hollow receptacles. During this operative stroke, rods 44 will lower the cross bar 43 which carries the trip-lever and treadle and when the arms 47 have been lowered sufficiently to clear the cross head 38, the weight of the arm 48 of 90 the lever will cause it to swing into position shown in Fig. 4 in readiness to act upon the cross head 38 for operating the ejectors at the end of the next separating stroke. After the product has been formed between the 95 dies, fluid under pressure will be admitted to the cylinders 23 to separate the dies. During the initial portion of the separating stroke, head 18 and dies 20 will be lifted away from the die block 12 and cross-bar 43 100 and lever 40 will be lifted. Toward the end of the separating stroke, arms 47 of the trip-lever will engage the cross-head 38 and operate the ejectors to lift the articles out of the dies 14. At the end of the separating 105 stroke, the parts will be in position shown in Fig. 6 and the movable die carrying head 18 will be at rest. Before commencement of the next working stroke of the movable die-carrying member, the operator will remove 110 the product from the upper ends of the ejector heads and after such removal he will depress the treadle 49 to trip lever 40 and release the cross-head 38 so that the springs 39 will restore the ejector heads 14 to their 115 normal position at the bottom of the dies 14. The operator will place charges of materials in dies 14, whereupon the press will be ready for another operative stroke. During the succeeding operating stroke, the trip lever 120 will be automatically shifted into position to operate the ejector at the end of the succeeding separating stroke as heretofore set forth.

The invention exemplifies an improved 125 fluid pressure operated press in which mechanism is provided whereby the ejector is operated by power to discharge the product from the dies and which can be manually tripped by the operator to restore the ejec- 130

tors to normal position before the fluid pressure operated member commences the next working stroke. As a result, the operator can, without danger of injury, place charges 5 of material in the dies while the movable die-carrying member is at rest or before the commencement of an operative stroke. The improved ejector mechanism is adapted to be applied to different die-blocks and is simple 10 in construction and efficient in operation.

The invention is not to be understood as restricted to the details set forth, since these may be modified within the scope of the appended claims, without departing from 15 the spirit and scope of the invention.

Having thus described the invention, what I claim as new and desire to secure by Letters Patent, is:

1. In a press, the combination of coacting 20 die members, fluid pressure mechanism for operating one of the members to and from the other, a product ejector and a trip device for the ejector supported by and operatively connected to said mechanism, and manually 25 operable to retract the ejector at all times while the members are separated.

2. In a press, the combination of coacting 30 die-carrying members, fluid pressure mechanism for operating one of the members to and from the other, a product ejector, and means for operating the ejector by said fluid pressure mechanism comprising a manually 35 operable lever mounted to be shifted bodily and supported by said mechanism and whereby the ejector may be retracted while the fluid pressure mechanism is idle.

3. In a press, the combination of coacting 40 die carrying members, fluid pressure mechanism for operating one of the members to and from the other, a product ejector and means for operating the ejector by said fluid pressure mechanism comprising a manually 45 operable trip-lever supported by and having an abutment arm for shifting the ejector and whereby the ejector may be retracted while the fluid pressure mechanism is idle.

4. In a press, the combination of a bed, 50 coacting die members, one of which is supported on the bed, fluid pressure mechanism for operating the other member, a product ejector in the stationary member, a trip device for the ejector, connected to and supported by the movable member.

5. In a press, the combination of a bed, 55 coacting die members, one of which is supported on the bed, fluid-pressure mechanism for operating the other member, a product ejector in the stationary member, and means for operating the ejector by said fluid pressure mechanism comprising a cross-head secured to move constantly with the movable die member and a manually operable trip lever pivoted on the cross-head and adapted to control the retraction of the ejector.

6. In a press, the combination of a bed,

coacting die members, one of which is supported on the bed, fluid pressure mechanism for operating the other member, a product ejector in the stationary member, and means for operating the ejector by said fluid pressure mechanism comprising a manually operable treadle supported by said mechanism and provided with means to engage and shift the ejector and whereby the ejector may be retracted. 75

7. In a press, the combination of coacting die-carrying members, fluid pressure mechanism for operating one of the members to and from the other, a product ejector, ejector-supporting means, and means for 80 operating the ejector by said fluid pressure mechanism comprising a trip lever mounted to be shifted bodily and supported by said operating means and operable to release the ejector-supporting means to retract the 85 ejector when the fluid pressure mechanism is at rest, and a lost motion connection between the lever and the ejector supporting means whereby the lever after releasing the ejector will be released to automatically pass 90 into operative position during the working stroke.

8. In a press, the combination of a bed, coacting die carrying members, one of which is supported by the bed, fluid pressure 95 mechanism for operating the other member, a product ejector slidable in the stationary member, a cross head below the bed to which the ejector is secured, a trip-lever below the bed for operating said cross-head and means for operating the lever by said fluid pressure mechanism to shift the cross-head and ejector, said lever being operable to release the ejector when the fluid pressure mechanism is at rest. 100

9. In a press, the combination of a bed, coacting die carrying members one of which is supported by the bed, fluid pressure mechanism for operating the other member, a product ejector slidable in the stationary 110 member, a lever below the bed for operating the ejector in one direction, spring-means for retracting the ejector, and means for operating said lever by said fluid-pressure mechanism, said lever being operable to release the 115 ejector for retraction by the spring-means.

10. In a press, the combination of a bed, coacting die carrying members, one of which is supported by the bed, fluid pressure mechanism for operating the other member, 120 a product ejector slidable in the stationary member, an ejector-supporting bar between the stationary member and the bed, a cross-head below the bed to which said bar is connected, a lever below the bed for operating 125 the cross-head in one direction, and means for operating the lever by said fluid pressure mechanism, said lever being operable for retraction of the ejector while the fluid pressure mechanism is at rest. 130

11. In a press, the combination of a stationary bed, brackets secured on the bed, a removable die carrying member mounted on the brackets, a movable coacting die-carrying member, fluid pressure mechanism for operating said movable member, a product ejector slidably mounted in the stationary member, a transverse bar disposed between said brackets and to which the ejector is secured, end-bars to which said cross-bar is removably secured, a cross-head below the bed, rods slidably mounted in the bed and secured to said end bars and to the cross head, and means operated by said fluid-pressure mechanism for operating the ejector comprising a trip lever operable to release the cross-head for retraction of the ejector while the fluid pressure mechanism is idle.
12. In a press, the combination of a stationary bed, brackets secured on the bed, a removable die-carrying member mounted on the brackets, a movable coacting die carrying member, fluid pressure mechanism for operating said movable member, a product ejector slidably mounted in the stationary member, a transverse bar disposed between said brackets and to which the ejector is secured, end bars to which said cross-bar is removably secured, a cross-head below the bed, rods slidably mounted in the bed and secured to said end-bars and to the cross-head, and means operated by said fluid pressure mechanism for operating the ejector comprising a cross-bar and a trip lever mounted on the latter and adapted to operate the cross-head when the fluid pressure mechanism is operated in one direction and manually operable to release the cross head for retraction of the ejector when the fluid pressure mechanism is idle.
13. In a press, the combination of a stationary bed, brackets secured on the bed, a removable die carrying member mounted on the brackets, a movable coacting die carrying member, fluid pressure mechanism for operating said movable member, a product ejector slidably mounted in the stationary member, a transverse bar disposed between said brackets to which the ejector is secured, end bars to which said transverse bar is removably secured, a cross-head below the bed, rods slidably mounted in the bed and secured to said end-bars and to the cross-head, and means operated by said fluid pressure mechanism for operating the ejector comprising a cross-bar and a trip lever mounted on the latter and adapted to operate the cross-head when the fluid pressure mechanism is idle.

EUGENE L. McGARY.
